United States Patent Office.

ALBERT SCHUNEMAN AND THEODORE SCHUNEMAN, OF DETROIT,
MICHIGAN.

Letters Patent No. 95,272, dated September 28, 1869.

IMPROVEMENT IN "PLUG-TOBACCO" CUTTER.

The Schedule referred to in these Letters Patent and making part of the same.

To all whom it may concern:

Be it known that we, ALBERT SCHUNEMAN and THEODORE SCHUNEMAN, of the city of Detroit, in the county of Wayne, and State of Michigan, have invented a new and useful machine for cutting plug-tobacco, called "The Improved Plug-Tobacco Cutter;" and we do hereby declare that the following is a full, clear, and exact description of the construction and operation of the same, reference being had to the annexed drawings, making a part of this specification, in which—

Figure 1 is a perspective view.

Figure 2 represents the cylinders C C, the adjustable bar D, the knife E, and the axle G.

Figure 3 represents the inside end of the cylinders C C, the end of the adjustable bar D, the end of the knife E, and the end of the fixed bar I.

Figure 4 represents a side view of the tube B, the aperture at the bottom, and the feed-box F.

Figure 5 represents a view of the tube B in a perpendicular position, showing the aperture in the bottom, and also of the aperture by which the feed-box F connects with the inner chamber of said tube.

Figure 6 shows a sectional end view of the tube B, the feed-box F, the upper aperture L, and the lower aperture M.

This machine consists of the horizontal cylindrical tube B, supported by the standards A A, as in fig. 1.

Within this tube are the two cylinders C C, fig. 2, in circumference corresponding with the circumference of the inner chamber of said tube, and located, one at each end of said chamber, occupying the spaces between the feed-box F, fig. 1, and the ends of the tube.

These cylinders are connected, first, by the fixed triangular bar I, fig. 3, which is fastened in grooves cut in the concave surface of the cylinders; second, by the horizontal double-edged knife E, fig. 2, fastened by screws into grooves cut in the cylinders; third, by the gauge-bar D, fig. 2, running parallel with the knife, having a bevelled edge toward the knife.

This bar is adjustable on planes wrought in said cylinders, by means of a latitudinal mortise cut through each end of such bar, through which the screws K K are inserted into the cylinders, enabling the operator of the machine to move the bar to or from the knife at pleasure.

From one of the cylinders C C, the axle G, fig. 2, projects outward through and beyond one of the standards to which the lever H H, fig. 1, is attached, by the use of which lever the cylinders C C, fig. 2,

the bars D and I, and knife E, are made to partially revolve within the tube B, fig. 1.

The tube is provided with an aperture on the under side, as represented in fig. 4, through which is discharged the tobacco when cut.

The tube is also mounted with the feed-box F, figs. 1 and 4, which connects by an aperture with the inner chamber.

The Object of the Machine, and the Mode of Using the Same.

Its object is twofold:

First, to cut plug-tobacco into sections.

To do this, take the plug of tobacco in the left hand and the lever H, fig. 1, in the right; pass the plug down through the feed-box F, fig. 1, and between the knife E and the fixed bar I, the ends of which are shown in fig. 3, until the desired point of severance is between the knife and the edge of the aperture in the tube at the bottom of the feed-trough; then, with the right hand, raise the lever, and, by so doing, the edge of the knife is brought against the tobacco and severs it.

Second, to cut plug-tobacco into small particles to any required degree of fineness.

To do this, adjust the bar D, fig. 2, according to the degree of fineness to which it is desired to cut the tobacco by moving it toward the knife, when the object is to cut the tobacco finer, and from the knife when a coarser kind is required; then, holding the lever perpendicularly, pass the tobacco down through the feed-box F, and press it against the bevelled edge of the bar D, which is shown in fig. 2; then move the lever rapidly first from, then toward the operator.

Inventors' Claims.

We claim—

1. The metallic hollow tube B and the metal cylinders C C, connected by the knife E and adjustable bar D, the same being constructed and arranged together in the manner and for the purposes set forth and described.

2. The application of the lever-power to the semi-rotary movement of the knife within the inner chamber, in the manner and for the purposes set forth.

ALBERT SCHUNEMAN.
THEODORE SCHUNEMAN.
